UNITED STATES PATENT OFFICE.

LOREN E. TAYLOR, OF LOS ANGELES, CALIFORNIA, ASSIGNOR TO FAMOUS PLAYERS-LASKY CORPORATION, OF NEW YORK, N. Y., A CORPORATION OF NEW YORK.

PROCESS FOR COLORING MOTION-PICTURE FILMS.

Application filed March 26, 1924. Serial No. 701,976.

To all whom it may concern:

Be it known that I, LOREN E. TAYLOR, a citizen of the United States, and a resident of Los Angeles, in the county of Los Angeles and State of California, have invented new and useful Improvements in Processes for Coloring Motion-Picture Films, of which the following is a full, clear, and exact disclosure.

10 This invention relates generally to processes for coloring motion picture films and particularly to the application of coloring matter, such as aniline dyes and the like, directly to the finished positive prints, so 15 they may be projected in colors, in any standard projector, without the aid of color filters or any special attachments.

The present process is closely allied with the invention covered by United States Letters Patent No. 1,303,837, granted May 13, 1919, wherein coloring matter is applied directly to finished positive prints by subjecting them to a pressurable contact with similar films carrying color matter; two 25 being, for this purpose, rolled in facial contact for a sufficient length of time to permit absorption of coloring matter by one from the other, while at the same time a longitudinal tension is exerted upon each of 30 the films, independently, to bring them into registering dimensions during their mobile contact.

Specifically, the instant case deals with the production of the color carrying films—hereinafter termed "print plates"—photographically; the foremost object being to simplify the production of these plates to a point of commercial practicability and economy.

40 In the production of print plates of this character, while they may be produced in other ways, it is preferable that they be prints or facsimiles of the original negative or positive to be colored, in order that the 45 several views or images therein may serve as bases for the application of the coloring matter, which will more or less perfectly register with the corresponding portions of similar views of the finished positive. 50 Therefore, as will be more fully hereinafter explained, the print plates in this case are made from prints of the original negative and positive, thereby simplifying and economizing production.

55 In the accompanying drawings I have

illustrated diagrammatically several of the steps in my process.

In these drawings,

Figure 1 represents a view taken from an original negative or a negative produced therefrom by printing back from a positive print;

Fig. 2 is a positive print taken from the original negative;

Fig. 3 is a view corresponding to the view shown in Fig. 1 after treatment according to my process; and

Fig. 4 is a view corresponding to that shown in Fig. 2 after similar treatment.

As the original negative, produced in the camera, is ordinarily preserved, the view shown in Fig. 1 will be deemed to be a view taken from a negative produced by printing back from a positive, such as shown in Fig. 2, but which corresponds to the original negative. Also the view of the positive film, shown in Fig. 2, will be deemed to be a print taken from the original negative and corresponding to the finished positive to be colored. In other words, the view shown in Fig. 1 is identical with the original negative, and the view shown in Fig. 2 identical with the finished positive to be colored. However, the original negative may be used for the purposes of this process, if desired.

The first step in my process is the production of an ordinary negative, by exposure in a camera of an orthochromatic film; that is, a film that is predominantly sensitive to the blue end of the spectrum and predominantly insensitive to the red. When such a negative is developed the blue will show relatively opaque; green shows more in half tone; yellow and pink still more in half tone and red practically clear.

Referring now to Fig. 1, for purposes of illustration, this view represents a red flower 10 having green foliage 11 setting in a brick red pot 12; the whole sitting upon a table over which is thrown a red cover 13. The numerals 14 designate blue curtains hanging in front of a window 15, and in front of which the flower and table are setting. Also for the purpose of this illustration the window will be deemed to be of clear glass through which a white light is passing.

After exposure of an orthochromatic film to the above described subject, when de-

veloped, the exposed area of the window 15, through which the white light is passing, will be opaque or substantially black; the curtains 14 being blue, to which the film is predominantly sensitive, will be very dark but not opaque; the areas covered by the flower 10 and table cover 13, will be clear, as such colors have little or no effect upon the film. The shrubbery 11 will be practically in half tone while the pot 12 will be more in half tone or only slightly darker than the areas 10 and 15. The negative print, just described, will ordinarily be produced by printing back from the positive print shown in Fig. 2; but for clarity of description it may be assumed that the negative shown in Fig. 1 is first produced, and that shown in Fig. 2 produced by printing therefrom.

20 After development of the negative shown in Fig. 1, a positive print, as shown in Fig. 2, is taken therefrom. In this positive print the gelatinous coating over the area 15, not having been acted upon by light is removed 25 in the developing process, leaving a surface consisting of only the clear celluloid base. The curtains 14 will show in a light half tone; while the flower 10 and table cover 13 will be black or substantially opaque. The 30 shrubbery 11 will be in substantially the same half tone as in the negative; while the pot 12 will be in half tone intermediate the tone of the shrubbery 11 and the cover 13.

It is to be understood in connection with 35 the foregoing description that various photographic values will be shown in the different portions of such a view, such as highlights in the flower 10, table cover 13 and curtains 14; and that these prints will show 40 the different photographic values in true proportions.

After production of the negative and positive prints, as above stated, they are both immersed in a chemical solution, which etches 45 out or eats away the gelatinous coating of the developed portions, that is, the portions affected upon by light, according to their different photographic values, or just in proportion as the silver is developed and effected by exposure to light. In other words, 50 the more opaque the surface, or the more fully the development due to exposure of light, the more thoroughly will the etching solution remove the gelatinous surface and leave only the clear celluloid base. The results from these steps of the process are 55 illustrated in Figs. 3 and 4, which represent the treatment of the films illustrated in Figs. 1 and 2, respectively; Fig. 3 representing the etched negative print of Fig. 1, and Fig. 4 representing the etched positive of Fig. 2.

In Fig. 3 I have represented the action of the etching solution upon the film by vertical lines, which shows that all the silver has

been removed from the areas covered by the blue curtains 14 and the window opening 15, leaving these portions practically clear. The foliage 11 has also been etched out until it is practically clear; while the areas covered by the flower 10 and table cover 13 are left untouched as they were originally, as shown in Fig. 1. The pot 12 has been etched until it is a half tone just a little darker than the flower 10 and cover 13.

75 In Fig. 4, inasmuch as there has been no silver coating on the area 15, after emerging from the developing process, this surface is still of the clear celluloid base, the same as in Fig. 2. The curtains 14 are shown in half tone, or more or less translucent; while the darker areas of the flower, the pot 12 and table cover 13, will be etched away, and the foliage 11 more or less in half tone, the same as the curtains 14. Therefore, in this view, 80 practically all that is left is the gelatinous surface over the areas 14 and the area 11.

85 After the aforementioned steps, the etched negative of Fig. 3, is immersed in an orange-red dye, or a color complementary to the color to which the original was predominantly sensitive; and as practically all the gelatinous surface remaining thereon is that upon the areas 10, 12 and 13, these areas will 90 absorb the dye in proportion to the remaining photographic values. The etched positive print, as shown in Fig. 4 is then immersed in a blue green dye, or the color to which the original negative was predominantly sensitive, which is absorbed by the 95 gelatinous surface 14 of the curtains, and the foliage 11; this being practically all the gelatinous coating left upon its face. Also, in this case, the dye is absorbed by these gelatinous surfaces in proportion to the different 100 photographic values.

105 From the foregoing description it is obvious now how I produce both an orange-red and a blue-green color print plates from the original negative and positive, either of 110 which may be brought into pressurable contact with the finished positive print, for the transfer thereto of coloring matter; and that the coloring matter carried by these 115 print plates is upon corresponding portions of views identical in position and size with the corresponding portions of the finished positive. While I have shown and described my process thus far as applied to the production of pictures of still subjects, it is 120 perfectly clear that print plates of this character may be produced of moving objects, where they occupy successively different positions in successive views.

125 After the production of the print plates, as hereinbefore described, they are successively rolled in contact with the finished positive, by means of a machine such as disclosed in the above mentioned patent, or by any other suitable means, and the color- 130

ing matter carried thereon absorbed, in proper proportions, by the finished positive. By finished positive I mean a positive print of the original negative which is intended to 5 be exhibited by projection.

The use of the term "negative", in the foregoing description, is to be construed to mean either the original negative produced by exposure of a film in a camera, or a similar film produced by printing back from 10 a positive or similar print of the original negative; while the term "positive print" pertains to a print of the original negative, or facsimile thereof, to be used as a color 15 plate, as distinguished from the finished positive to be colored and exhibited.

What I claim is:

1. The process of coloring motion picture films comprising producing a negative by 20 exposure of a film predominantly sensitive to certain colors and predominantly insensitive to colors complementary thereto, taking a positive print therefrom, etching out those portions of the sensitized coating of the negative containing the silver affected by exposure to light, applying coloring matter to 25 said etched negative so that it is absorbed by those portions of its gelatinous coating not removed by etching, said color being complementary to the color to which the negative was predominantly sensitive, and transferring said coloring matter to the positive film by bringing it into pressurable facial contact therewith.

35 2. The process of coloring motion picture films comprising producing a negative by exposure of a film predominantly sensitive to certain colors and predominantly insensitive to colors complementary thereto, taking a positive print therefrom, etching out those portions of the sensitized coating of the positive print containing the silver affected by exposure to light, applying coloring matter to 40 said etched positive print so that it is absorbed by those portions of its gelatinous coating not removed by etching, said color being the same as that to which

the negative was predominantly sensitive, and transferring said coloring matter to a similar positive print of said negative by 50 pressurable facial contact therewith.

3. The process of coloring motion picture films comprising producing a negative by exposure of a film predominantly sensitive to certain colors and predominantly insensitive to colors complementary thereto, taking a positive print therefrom, etching out those portions of the sensitized coatings of said negative and positive containing the silver affected by exposure to light, applying coloring matter to said etched negative and positive so that it is absorbed by those portions of its gelatinous coating not removed by etching, the color applied to the etched negative being complementary to the color to which it was predominantly sensitive, and the color applied to the etched positive being complementary to the color applied to the negative, and the transfer of the coloring matter applied to said negative and positive to a positive print of said negative by 60 successively bringing them into pressurable facial contact therewith.

4. The process of coloring motion picture films comprising producing a negative by 65 exposure of a film predominantly sensitive to the blue end of the spectrum and predominantly insensitive to the red end, taking a positive print therefrom, etching out these portions of the sensitized coatings of said negative and positive containing the silver affected by exposure to light, in proportion to their photographic values, applying orange-red dye to the gelatinous face of the etched negative, applying blue-green dye 70 to the gelatinous face of the etched positive, and thereafter transferring the coloring matter from each of said films to a positive print of said negative by bringing them into 75 pressurable facial contact therewith.

In witness that I claim the foregoing I have hereunto subscribed my name this 4th day of March, 1924.

LOREN E. TAYLOR.
